(57) **CLAIM**

The ornamental design for the three-port shower header adapter, as shown and described.

DESCRIPTION

FIG. 1 is a perspective view of the unique three-port shower header adapter in accordance with the invention;

FIG. 2 is a top plan view of the three-port shower header adapter of FIG. 1;

FIG. 3 is a left side plan view of the three-port shower header adapter of FIG. 1 (with the right side plan view being a mirror image thereof);

FIG. 4 is a bottom plan view of the three-port shower header adapter of FIG. 1;

FIG. 5 is a front plan view of the three-port shower header adapter of FIG. 1; and,

FIG. 6 is a rear plan view of the three-port shower header adapter of FIG. 1.
